CLAIM

The ornamental design for a scissors, as shown and described.

DESCRIPTION

FIG. 1 is a front perspective view of the scissors according to the present invention, illustrating the scissors in a folded configuration;

FIG. 2 is a perspective view of the scissors of FIG. 1, illustrating the scissors in an unfolded configuration;

FIG. 3 is a front elevational view of the scissors of FIG. 1; FIG. 4 is a right-side elevational view of the scissors of FIG. 1;

FIG. 5 is a rear elevational view of the scissors of FIG. 1; FIG. 6 is a left-side elevational view of the scissors of FIG. 1;

FIG. 7 is a top plan view of the scissors of FIG. 1; and, FIG. 8 is a bottom plan view of the scissors of FIG. 1.

The broken lines shown on the drawings are for illustrative purposes only and form no part of the claimed design.
